UNITED STATES PATENT OFFICE.

WILLIAM W. PUTNEY, OF KENT CITY, MICHIGAN, ASSIGNOR OF ONE-FOURTH TO MICHAEL A. MUMA AND ONE-FOURTH TO EDWARD M. HOLLAND, BOTH OF GRAND RAPIDS, MICHIGAN.

CHAMFER, CROZE, AND EQUALIZING KNIFE FOR STAVE-MACHINES.

1,170,187.

Specification of Letters Patent.

Patented Feb. 1, 1916.

Application filed March 4, 1915. Serial No. 12,071.

To all whom it may concern:

Be it known that I, WILLIAM W. PUTNEY, a citizen of the United States of America, residing at Kent City, in the county of Kent 5 and State of Michigan, have invented certain new and useful Improvements in Chamfer, Croze, and Equalizing Knives for Stave-Machines; and I do hereby declare the following to be a full, clear, and exact description of the invention, such as will enable others skilled in the art to which it appertains to make and use the same.

This invention relates to a chamfer, croze and equalizing knife for stave machines of 15 the type for cutting staves for barrels, casks and like articles of manufacture wherein a stave bolt is acted upon by cutters in a stave cutting machine to sever the staves from the bolt and at the same time chamfer and croze 20 said staves.

It is the object and purpose of this invention to provide a knife of this character which may be used in stave cutting machines of ordinary type, especially in those machines known as the Greenwood machines, 25 and which will so act upon the stave bolt that it will simultaneously cut the chamfer, and croze and cut off the extended end of the bolt beyond the desired length of stave in 30 the same plane with the stave, whereby at any time if desired the stave bolt may be reversed in the machine and thereafter operated upon.

It is also purposed in this invention to 35 provide a novel type or kind of shimming knife to be used in connection with the stave chamfering and crozing knife for trimming off the ridge of material on the stave formed as the preceding stave has had the croze and 40 chamfer cut therein at the same time by reason of the relative locations of the knives always cutting all the staves at the ends thereof to the same thickness irrespective of the thickness of the staves between the ends.

45 For an understanding of the construction by which these ends are attained reference may be had to the accompanying drawings in which;

Figure 1 is a perspective view of a stave 50 cutting machine with my improved knife in use therein. Fig. 2 is an end view of said machine with parts broken away to disclose the structure; and Fig. 3 is a perspective

view of the chamfer and crozing knife and of the shimming knife showing the manner 55 in which they are associated in forming the stave end, the position of the knives being at right angles to normal position to better show their coöperation.

Like reference characters refer to like 60 parts throughout the several views of the drawing.

The stave machine itself is comprised of spaced apart end supports 1 having located therebetween the horizontal connecting 65 members 2 and 3 and supporting a central knife section 4 having its cutting edge downwardly extending for cutting the central portion of the stave, said knife at either end having in conjunction therewith the chamfer and crozing knives 5 which form an essential feature of my present invention. In the operation of cutting the stave a bolt rests at its ends on the curved ways 6 and lies against the movable table 7 pivotally mounted 70 at its ends at 8 to the end members 1 of the machine, said table being operated in an upward direction by force applied to the yoke 9 which extends downwardly from said table as shown. The stave bolt in this manner is brought against the knives 4 and 5, 75 the cutting edges of which are set forward a distance equal to the thickness of a stave in front of ways 6.

Specifically the knife 5 comprises a metal 80 plate having a sharpened lower edge 10 and provided with two grooves 11 and 12 between the side edges thereof the lower edges of the metal forming the grooves also being sharpened while upon the rear edge of the 90 plate at the angle formed by the groove 12, a rib 13 is integrally cast, it also having a sharpened lower edge. The lower edges of the plate from which the knife 5 is formed excepting those portions forming grooves 11 and 12 are in alinement. Groove 11 is of 95 comparative narrow width and as the stave bolt is forced against the cutting edge thereof, the croze of the stave is formed. Groove 12 is wider and as the stave is cut from the 100 bolt the chamfer is formed by the cutting edge of said groove which lies between the groove 11 and rib 13, said rib cutting the stave off to proper length.

Secured to the cross piece 3 of the stave 105 cutting machine adjacent but a short dis-

tance back of the groove 11 of each knife 5 is a shimming knife 14 having a curved section 15 with an outwardly flared portion 15^a and terminating in the cutting edge 16 which as a stave is cut from the stave bolt trims off the residue of material left when the croze and chamfer of the previous stave was formed. It will be observed that this shimming knife 14 is adjustable back and forth with relation to the knife 5 and that it may be adjusted to any desired position with relation thereto. It will also be apparent that the said residue of material is cut away simultaneously with the cutting 10 of the stave from the bolt, so that every stave cut is of exactly the same thickness as its end, and a series of said staves are capable of being made into a barrel of standard size a result impossible of attainment 15 heretofore owing to the fact that when the shimming knife acts after the stave cutting knife the vibration of the stave produces inequalities and when it cuts from the bolt before the action of the cutting knife there 20 is a tendency for the bolt or knife to jump chatter making imperfect and irregular cuts as will be apparent. The edge of the knife comes immediately within the position occupied by the rib 13 so that it may be adjusted closer to knife 5 than would be the case 25 if any portion of knife 14 was back of the rib 13. At times it is desired to cut the ends of the stave thin, at other times it may be desired that they shall be of greater 30 thickness and this is effected in my machine by the adjustment of the knife 14 with respect to the knife 5 as described, but in all cases all the staves cut from a bolt after the shimming knife is once adjusted are of the 35 same thickness at the ends.

In the operation of this machine, a stave bolt may be placed therein and the table 7 operated back and forth to cut staves therefrom. The sections of the knives 5 beyond 40 the wider grooves 12 will cut the ends of the bolt beyond the ribs 13 in the same plane and in alinement with those portions of the bolt normally acted upon by the knife 4 and by those sections of the knives 5 adjacent the grooves 11. In this way the 45 surface of the stave that has been acted upon by the knife presents a substantially plane appearance except where acted upon by the grooved portions of the knives and said 50 stave may be reversed at any time if necessary or advisable on account of the grain or other characteristics of the stave bolt. This is a very essential feature of my invention and one of considerable practical value. The 55 shimming knife used in conjunction with the chamfer and crozing knives is of novel formation and its curved end lying back of the stave as it is cut from the bolt is in best position to remove the residue of material 60 left in making the croze on the previous 65

stave permitting the initiation of the cut of the stave from the stave bolt earlier than the shimming knives of previous stave machines of this character, said machines ordinarily having the shimming knife with its cutting edge located below the cutting edge of the stave knife; also as heretofore pointed out the novel position of the trimming knife with relation to the cutting knife 15 makes it possible to cut the staves at their 15 ends of any desired thickness. It will also be evident that the flared out portion 15^a serves as a guide to throw the material removed by the shimming knife outwardly to one side preventing any of such material 20 from coming back upon the bolt and interfering in any way with the operation of the cutting knives thereupon.

From the foregoing it will be evident 25 that I have provided a simple and very efficient knife for simultaneously cutting, crozing and chamfering staves, the ends of the stave as indicated at 17 in Fig. 3 being completely formed with the one operation.

My invention is defined in the appended 30 claims and all modifications in structure falling within their scope are to be considered as comprehended within said invention.

1-claim:—

1. In a stave cutting machine, the combination with a table on which a stave bolt is placed of a central knife for cutting the central portion of the stave and an auxiliary chamfering, crozing and equalizing knife 100 in alinement with and at each end of the central knife to cut, chamfer and croze a stave at a single operation, said auxiliary knives having extensions beyond the chamfer and crozing portions thereof in alinement with the central knife for cutting the ends of the stave bolt beyond the length of the stave cut therefrom in the same plane with the central portion of the stave bolt.

2. A chamfering, crozing and equalizing knife for stave machines comprising a plate having a sharpened edge a pair of adjoining grooves in said knife one of which is comparatively narrow and the other of comparatively greater width, and a rib having a sharpened edge on the back of said knife opposite the lowermost point of the wider groove, the edge of the knife at either side of the grooves being in alinement, substantially as described.

3. In combination, a chamfering, crozing and equalizing knife for use in stave machines, a shimming knife including a portion adapted to be secured to a stave machine and a forward curved extension terminating in a downwardly extending sharpened edge located directly back of the cutting edge of the chamfering, crozing and equalizing knife whereby the cutting edges of said knives engage a stave bolt at substantially 125 130

the same time, and means on the shimming knife to direct the material severed thereby away from the knives.

4. In combination, in a stave cutting machine, a chamfering, crozing and equalizing knife having a rib on its rear side, a shimming knife adjustably mounted with one side adjacent said rib and having its cutting edge substantially directly back of the edge 10 of the cutting knife whereby said cutting edges of the knives engage the work at substantially the same time, said shimming knife being adjustable in a direction substantially normal to the edge of the chamfering, crozing and equalizing knife that the thickness of staves at the ends thereof, cut by said knives may be varied, substantially as described.

5. In combination, in a stave cutting machine, a knife having a crozing groove and a chamfering groove, a rib having a sharpened lower edge on the knife back of the chamfering groove, a shimming knife mounted to move back and forth in a direction substantially normal to the edge of said knife, said shimming knife adapted to pass on the inner side of the rib and having a curved forward end terminating in a cutting edge 25

directly back of the cutting edge of said knife, and means on the shimming knife to 30 direct the material cut thereby laterally away from the knives, substantially as described.

6. In combination, in a stave cutting machine, a knife having a crozing groove and 35 an adjacent chamfering groove, a rib having a sharpened lower edge on the knife back of the chamfering groove, a shimming knife positioned directly back of the cutting edge of said knife and having its outer edge in 40 a plane within the inner face of the rib having a forward end curved upwardly and then downwardly terminating in a cutting edge directly back of the cutting edge of 45 said knife, and an upward and outward flare to the curved portion of the shimming knife to guide the material cut by the shimming knife away from the knives and the material operated on by said knives.

In testimony whereof I affix my signature 50 in presence of two witnesses.

WILLIAM W. PUTNEY.
